ATTY.

UNITED STATES PATENT OFFICE.

WILLIAM WEIR HENRY, OF WOLLASTON, MASSACHUSETTS, ASSIGNOR TO S. H. COUCH COMPANY, INC., OF ATLANTIC, MASSACHUSETTS, A CORPORATION OF MASSACHUSETTS.

HAND-MICRO TELEPHONE.

1,204,765.

Specification of Letters Patent. Patented Nov. 14, 1916.

Application filed June 19, 1914. Serial No. 346,153.

To all whom it may concern:

Be it known that I, WILLIAM WEIR HENRY, of Wollaston, a citizen of the United States, and residing at the above place, in the 5 county of Norfolk and State of Massachusetts, have invented certain new and useful Improvements in Hand-Micro Telephones, of which the following is a specification.

This invention relates to hand-micro telephones, and has particular reference to the unit system of mounting the various parts upon the frame, as well as to the various improvements in the detail of switches, transmitter mountings, etc., as will later appear.

15 The demands of the trade require various styles of hand-micro telephone equipments, from those using but two sets of transmitter and receiver mechanism, connected by a single circuit and battery, to those which 20 furnish a number of circuits for inter-communication. I have found it desirable to form the circuit connectors or terminals upon a single, removable base-plate which is adapted for mounting upon the frame at 25 any point distant from the assembly room, and, in this manner, the same frame is adapted, without change, for any system of wiring desired.

In the drawings, which form part of and 30 accompany this specification, and which illustrate the preferred form of my invention,—Figure 1 is a vertical, central section of my assembled unit. Fig. 2 is a rear, plan view, with cover removed. Fig. 3 is a section on line 3—3 of Fig. 1, enlarged. Fig. 35 4 is a section on line 4—4 of Fig. 1. Fig. 5 is a detail. Fig. 6 is a diagram showing one form of wiring.

The frame 1 is preferably made of a flat, 40 metal plate with a suitable aperture 2 by which the phone may be hung against the wall when not in use. The receiver 3, of ordinary construction, is mounted on frame 1 by means of screws 4.

45 The transmitter 5 is mounted at the other end of frame 1 by means of screws 6. By an inspection of the drawings, it will be noticed that by this method of mounting, the transmitter, receiver and frame constitute what I will call unit number one, the 50 same being adaptable, without change, for different circuit connectors which may be in turn mounted upon the base-plate 7 of unit number two, the latter to be now described.

Base-plate 7 is preferably of pressed metal construction, with outline somewhat smaller than frame 1, so that cover 8 may form a neat closure with frame 1. Base-plate 7 is provided with openings to register with two 60 pilot pins 9 which are struck up from frame 1 for easy assembling, and the two screw-posts 10, which thread into frame 1, hold plate 7 firmly in place. Base-plate 7 is properly punched and threaded to receive 65 the circuit connectors and push-buttons, the latter being adapted to project through suitable openings in frame 1.

I have illustrated plate 7 as supporting four vertical pairs of connectors, of which 70 the upper (or rear) are lettered A, B, C and D. The corresponding lower connectors are lettered *a*, *b*, *c* and *d*. The first three pairs are for talking and for receiving a bell call, the last being adapted for sending a 75 ringing call to some distant unit. A and *a* are shown (see Fig. 3) as being electrically united to furnish the common wire connection. B and *b* and C and *c* are shown insulated from each other, and each must have 80 its separate wire, if it is to enter into the scheme of circuits. It will be noticed that connectors A, B, C, *a*, *b* and *c* are shown 85 as being rigid, connections being made through the agency of a multiple tined flexible switch 15, secured to the insulated base 16 of the push-button 17 by a screw 18, and held in place by the pilot pins 19. The purpose of using a flexible switch (which is not directly wired to any connector) is to 90 secure a wiping contact of a positive character, thus insuring good connection.

By forking the switch 15, I secure greater elasticity and also prevent any interference in the contacts, in case of slight variations 95 of assembling; that is to say, with the switch 15 formed in one broad band, one of the contacts might be weakened by reason of the undue prominence of one of the other connectors.

100 Push-button 17 is mounted on a flat, metal spring 20, the latter being secured to plate 7 by screw 21. Pilots 22 and 23 serve to maintain the relative positions of the parts and an ear 24 on spring 20 furnishes a stop 105 for the yielding of button 17, when under pressure. Push-button 25 is shouldered, as at 26, to prevent its dropping out when unit number two is separated from unit number one.

Suitable openings 27 and 28 are provided in base-plate 7 and frame 1 for the assembling of the wires. An opening 29 in cover 8, provides for the entrance of the cord.

5 Referring to Fig. 2, the form of service rendered by switch member 15 will now be noticed.

Assume that connectors B and C are wired in the talking circuit so that there is 10 a break that must be bridged by switch 15. Also, assume that connector b is wired in the circuit for receiving a ring from a distant button similar to 25. As shown, switch 15 closes the latter circuit, so that the signal 15 will be properly received, when the bell connections (not shown) are properly made. The recipient presses his button 17, thus breaking the ringing circuit and closing the talking circuit by uniting A (the common 20 wire connector) B and C, with a wiping contact.

In mounting the mouth-piece 30 on transmitter 5, it is desirable that the receiving orifice 31 shall occupy a definite position 25 with respect to receiver 3. As the threaded shank of mouth-piece 30 is screwed to a shouldered nipple 32 which is held within the casing 33 of transmitter 5, I preferably form nipple 32 with a lug 34 adapted to 30 occupy one of a series of notches 35 arranged around the periphery of the opening 36 which receives nipple 32. If it is found that mouth-piece 30 does not register properly, it may be slightly unscrewed and, 35 by pressing inward, the lug 34 disengages its particular notch 35, whereby nipple 32 may be turned to bring lug 34 opposite another of the notches 35. By selecting the proper notch 35, mouth-piece 30 may be 40 brought into proper register with the receiver 3. A spring 37, preferably formed with three feet 38 (see Fig. 4) may be employed to retain the nipple 32 in position when mouth-piece 30 is unscrewed.

45 I do not limit myself to the precise construction illustrated.

What I claim is: —

1. In a hand-micro telephone, a transmitter casing adapted to be mounted on a suitable frame, a curved mouth-piece adapted to be screwed into position against said casing, said casing having a notched opening adapted for the projection therethrough of a threaded nipple; in combination with a 50 threaded nipple or bushing adapted to receive the end of said mouth-piece, said nipple being provided with a projection

adapted to alternately engage anyone of the notches surrounding said opening for the purpose of preventing relative rotation of 60 said nipple when so engaged.

2. In a hand-micro telephone, a transmitter casing adapted to be mounted on a suitable frame, a curved mouth-piece adapted to be screwed into position against said 65 casing, and a threaded nipple or bushing adapted to receive and secure said mouth-piece against said casing, means for adjustably securing said nipple against rotation upon and within said casing, and elastic 70 means for holding said nipple in locked position upon said casing.

3. In a hand-micro telephone, a frame whose face is adapted for the mounting thereon of suitable receiver and transmitter 75 mechanism; a metallic base-plate adapted for the mounting thereon of all the necessary buttons and switches; means for removably securing said base-plate to the back of 80 said frame; and a cover adapted to be secured over said base-plate.

4. In a hand-micro telephone, a frame adapted for the mounting thereon of suitable receiver and transmitter mechanism; a metallic base-plate adapted for the mounting thereon of all the necessary buttons and 85 switches; means for removably securing said base-plate to said frame; and a cover adapted to be secured to said means.

5. In a hand-micro telephone, a frame 90 whose front is adapted for the mounting thereon of suitable receiver and transmitter mechanisms; a metallic base-plate adapted for the mounting thereon of all the necessary switches and buttons; means for removably securing said base-plate to the back of 95 said frame; means whereby said buttons may be manipulated from the front of said frame; and means for inclosing said switches. 100

6. In a hand-micro telephone, a frame adapted for the mounting thereon of suitable receiver and transmitter mechanisms; a metallic base adapted for the mounting thereon of all the necessary buttons and 105 switches; means for removably securing said base to said frame; and covering means adapted to conceal said switches.

In testimony whereof, I have affixed my signature, in the presence of two witnesses. 110

WILLIAM WEIR HENRY.
